UNITED STATES PATENT OFFICE.

GEORGE M. CONWAY, OF MILWAUKEE, WISCONSIN.

SHAKING AND DUMPING GRATE.

SPECIFICATION forming part of Letters Patent No. 556,403, dated March 17, 1896.

Application filed May 2, 1893. Serial No. 472,722. (No model.)

To all whom it may concern:

Be it known that I, GEORGE M. CONWAY, a citizen of the United States, and a resident of Milwaukee, in the county of Milwaukee, and in the State of Wisconsin, have invented certain new and useful Improvements in Shaking and Dumping Grates; and I do hereby declare that the following is a full, clear, and exact description thereof.

10 My invention relates to shaking and dumping grates; and it consists in certain peculiarities of construction and combination of parts, as will be fully set forth hereinafter and subsequently claimed.

15 In the drawings, Figure 1 is a side elevation of my improved device with parts broken away and shown partly in section on the line 1 1 of Fig. 2. Fig. 2 is a plan view of a portion of my device with portions thereof broken

20 away or removed and partly in section. Fig. 3 is a partly vertical sectional view on the line 3 3 of Fig. 1. Figs. 4 and 5 are detail sectional views of the grate-sections in different positions, Fig. 4 being taken on a section

25 through the central portion of the grate-sections, and the section-line of Fig. 5 being taken adjacent to the end of the grate-sections beyond the last side extensions of the transverse bars, which therefore do not show in said Fig.

30 Figs. 6 and 7 are enlarged detail views of portions of the frame.

Heretofore in shaking and dumping grates as ordinarily constructed the grate-sections have been arranged to dump only one way, and with such ordinary grates the moment they begin to turn in the act of shaking the space between each two adjacent sections increases as the grate is turned, allowing the material resting thereon to fall down through 35 between said sections, occasioning much waste thereby, whereas in my grate the sections are arranged to dump either way, and are so constructed that the space between each two adjacent sections, while passing through an angle of thirty degrees or more either way from their normal vertical line in shaking, will remain always the same, and this operation of shaking within the angular limits named will sufficiently disturb the material resting on 40 the grate to free it from dust, ashes, or whatever substance is to be eliminated therefrom

and break up incrustation and effectually prevent the material from filling up the grate and its interstices, as in the case of burning a refuse coal, where slag and clinkers are liable 55 to form, without permitting the valuable part of said material to dump down between said sections and become lost. Then by passing from the said angle of thirty degrees or more to an angle of sixty or more degrees the space 60 between the sections will increase sufficiently to enable the material to be dumped, and by the reversing process rendered possible by my construction the sections can be turned back and forth from one side to the other, 65 so that the described incrustation, already broken by the shaking, can be reduced to such size as to cause all portions thereof which 70 lodge between said sections to become still further reduced and fall down through between the sections in dumping. These results are attained by reason of the construction which I will now proceed to describe.

As shown in the drawings, the grate is arranged for use in connection with a horizontal cylindrical boiler, though it will be understood that it is adapted for any kind of furnace or drying floor desired.

My grate rests upon its own supports independently of the surrounding walls.

80 A represent the legs or supports of my device.

B B represent the horizontal end frames of the device, which interlock with the top of the legs A A in this manner. Each of the 85 legs A has a central vertical inner web a, the upper part of which web has a cross-head a', and said legs have enlarged bases or feet a². At points directly over said legs the end frames B are formed, as shown in detail, Fig. 90 7, with downward-forked flanges b b (designed to embrace the described webs a of the legs A between the transverse outer edge of the said legs and the cross-head a') and horizontal flange b' at the top of the forked flanges 95 b b, so that when the end frames B B are dropped to place on the legs A A all parts will be held firmly together, the horizontal flange b' resting on the top of the web a and cross-head a'. In addition, the frames B B have 100 vertical angle-flanges b² b² on their inner sides, above the flanges b b and rising to the height

of the said frames B. All these parts (shown in Fig. 7) are cast solidly and integral with the said frames B.

C C represent the two side bearing-bars, 5 and D the center bearing-bar of the frame. The ends of these bars are provided with cross-heads c for engagement with the angle-flanges b² b² of the frames B, back of which are the flanges d having right-angular bottom extensions d³ for the ends e of the stationary outer grate-sections E hereinafter described. The bars C are each provided on the inner side with a series of round hubs c', perforations c² extending through the center of said hubs 10 and through the side bearing-bars in line therewith, as shown best at the left hand in Fig. 3. The bars C are further provided with projecting arms c³ on the outer side, and the end frames B are similarly provided with end flanges b³, both the arms c³ and flanges b³ being designed for the support of the webs f on the under side of the perforated inclined plates F hereinafter described.

The center bearing-bar, D, is provided on 25 both sides with hubs d' having perforations d² therethrough and through the said bar in line therewith, as best shown in the center of Fig. 3, similar to the hubs c' on the bars C; but unlike those hubs c' the hubs d' are not 30 wholly round, but are cut away on the under side, as shown at d⁴, to enable the grate-sections to be placed on or removed from the hubs separately without disturbing the end frames and side and center bearing-bars. 35 The center bar, D, is further provided with a series of teeth d⁵ d⁶ arranged at intervals to fill up the space that would otherwise be left between the adjacent ends of grate-sections, next described:

40 The stationary outer grate-sections E, already named, comprise a central vertical web, (whose ends e e rest on the flange extensions d³ of the bearing-bars C C, as already stated, between the flanges d on said bars and the 45 adjacent flanges b² of the end frames B,) said web being provided at each side with obliquely-inclined teeth projecting inward and downward from one side of said web and outward and upward from the other side thereof, as shown best in full lines on the right-hand side and in dotted lines on the left-hand side of Fig. 1. Only one of these stationary 50 outer grate-sections E is shown in Fig. 2, but it will be understood that there are four of them in this form of my device, all parallel with the said end frames B B, and as they converge from the said outer end frames B B inward they form practically two sides of a 55 hopper formation, the other sides of which 60 consist of the hereinbefore-named inclined perforated side plates F F.

The shaking and dumping grate sections 65 comprise outer sections G H, which are right and left handed complements, and intermediate sections I I, which are of uniform conformation. Each of these sections comprises inner end pieces, g h and i i, with rounded

tops and vertical parallel sides and having lower lever extensions, g' h' i' i', as best indicated in Fig. 5, which latter are connected by 70 pivots j j with a parallel connecting-bar J, which latter is connected by forked head j' and pivot k to the connecting-rod K, which extends from this point to the shaking-lever M, hereinafter particularly described, to 75 which the rod K is pivoted, as shown by the pivot-pins L. In addition, each of the said inner ends of the grate-sections have circular openings g² h² i² i² therethrough to receive the described hubs d' d' on the center bearing-bar, D. The outer ends of the grate-sections g³ i³, &c., are correspondingly rounded on top and have slotted openings g⁴ i⁴, &c., in their lower edges to pass down over the hubs c' c' on the side bearing-bars, C C, said ends being 80 extended downward below the hub-line and transversely perforated to receive locking-pins g⁵ i⁵, &c., just below the lower line of said hubs.

The intermediate grate-sections I I are each 90 composed, in addition to the already-described parts, of a series of transverse bars, rounded on top in conformity with the curvatures of the described inner end pieces, but which project beyond the line of the described vertical parallel sides, the said grate-sections at the line of these bars being transversely of spherical triangular shape, as clearly indicated by the two intermediate grate-sections in Fig. 4. The outline of the outer end pieces 95 of these said intermediate grate-sections is of corresponding form down to the base of the described hub-line. The outer movable grate-sections, G H, have similar series of transverse bars, which are of similar form on the 100 top and inner sides; but the outer sides of said sections G H are modified, as shown at the right and left in Fig. 1 and at the left in Fig. 4, by being struck on a circle from the center of the openings, as h², that receive the 105 hubs d', forming a sector of said circle extending from the intersection of the said rounded top surface and adjacent vertical side of the grate-section down to the base-line of said vertical side.

The shaking-levers M (of which there is one for each set of grates, two being shown in the present illustration) are preferably of the general form shown in Fig. 1, and are pivoted, as already described, at L to the connecting-rod K, and also, as shown at n, to an arm or projection n' on a casting N, (which acts as the fulcrum of said lever,) the upper portion of which casting is preferably bifurcated, (as well as shown double in the form 115 illustrated for the two levers of the two sets of grates, that being a mere matter of convenience, however,) and in the opening of said bifurcated portion there moves a rearward extension of said lever M, having an 120 arc slot m. The said bifurcated casting has two holes therethrough, the upper one being in line with the radial line of movement of said slot m and the other just below it, and

registering, when the parts are in the position shown in Fig. 1, with a hole m' through the lever extension below said slot. O is a pin adapted for engagement with either of the 5 holes described, as circumstances may require. The lever M is provided with a suitable socket p for the reception of a lever-handle P, as shown.

The operation of my device will next be described, the parts being in the relative positions shown in Fig. 1, and it being understood, for the purpose of this explanation, that my invention is here shown as arranged for a coal-burning furnace, although, as heretofore 15 stated, not in any sense limited thereto.

The fuel is fed onto the upper surface of the grate and properly ignited, and when a sufficient quantity has been consumed to cause the resultant ashes and clinker to partially close up the orifices in the grate-sections it becomes necessary, in order to continue a proper combustion, to get rid of that deposit. This is accomplished by shaking the 20 grate-sections back and forth, as described, the limitations enforced by the relative arrangement of the pin O and the arc slot m in the shaking-lever serving, automatically, to keep the movement of the said grate-sections within the angular limits hereinbefore named. 25 without increasing the size of the openings between the adjacent grate-sections, and this, as already stated, will suffice to get rid of the dust, ashes, and like refuse matter without loss of fuel, the said space between the grate-sections in this position (shown in Fig. 4) being the same as when they are in their normal upright position. (Shown in Fig. 1.) When 30 in said normal position, the pin O is shifted to the lower hole, m' , and thereby the parts are rigidly locked and all movement of the 35 grate-sections prevented. As the ashes and other refuse matter are gotten rid of, as described, the fuel which is piled up against the obliquely-inclined plates F gradually settles down, and the ashes are liberated from the said plates and from the inclined stationary outer grate-sections. The 40 perforations in the said plates F are to admit air therethrough, and thereby aid in the combustion of the fuel, and the described hopper-like 45 formation of the inclined parts E E F F aid in keeping the fuel fed forward to the grate, as well as in the just-described liberation of refuse matter and in the operation of 50 dumping.

When it becomes necessary to dump the grate, the pin O, which is preferably secured by a chain (not shown) to some adjacent portion of the structure, is wholly removed and 55 dropped down, and then the lever M is operated by means of the handle P to its fullest extent back and forth, whereby the grate-sections assume at each end of the movement the relative positions shown in Fig. 5, the 60 openings between the adjacent grate-sections amounting to nearly forty per cent. of the entire grate area, instead of only about six

per cent. thereof when the said sections are in either their normal or shaking positions, and consequently the grate is very quickly 65 dumped.

My grate-sections are preferably strengthened by central transverse webs i^6 , as shown in Fig. 3, and all parts of said sections are cast solidly in one piece. The hubs upon 70 which said grate-sections are supported, as well as the bearing-bars of which said hubs form portions, are made hollow or perforated at these points, as described, for the purpose of securing a circulation of air therethrough, 75 and aiding thereby in keeping the said parts comparatively cool in use, and by reason of the described cut-away portions d^4 of the hubs d' on the center bearing-bar D and the slotted openings g^4 i^4 , &c., at the opposite end 80 of the grate-sections G I, &c., the said sections can, as already stated, be readily dropped to place and then secured against accidental displacement by means of the described locking-pins g^5 i^6 , &c., which pins can be easily 85 removed for the withdrawal of any of said grate-sections in the reverse manner, it being, of course, necessary to remove the split locking-pins g^7 i^7 h^7 , which secure the pivots j on the lower ends of the lever extensions g^1 i^1 h^1 90 of the grate-sections to the parallel connecting-bar J, before this removal can take place, and to secure such locking devices in place when the grate-sections are adjusted.

In place of the described connecting-bar J 100 and connecting-rod K any suitable connecting device may be employed, so far as the described operation of my grate-sections is concerned, but I have found the means described to work well in practice.

A valuable feature of my present device lies in the fact that the entire frame is so constructed as to be readily removable at all parts for the replacement or repair of a broken portion, and is all put together and held rigidly in place without the use of a single nut or rivet, and hence the injury arising from the burning, breaking or warping of such securing devices in other shaking and dumping grates is wholly obviated.

Having thus described my invention, what I claim as new, and desire to secure by Letters Patent, is—

1. In a shaking and dumping grate, a series of intermediate movable grate-sections, each comprising vertical parallel sides connected by transverse bars integral therewith and projecting beyond the line of said sides, and having integral end pieces, said grate-sections at the line of said bars being transversely of spherical triangular shape, and outer movable grate-sections, corresponding at the top and inner sides with the shape of the said intermediate grate-sections, but each having its outer bar extensions forming a 125 sector of a circle extending from the intersection of the rounded top surface and adjacent vertical side of the said grate-section down to the base-line of the said vertical side.

2. In a shaking and dumping grate, the combination with a suitable socketed frame, and a series of movable grate-sections connected together and mounted therein, of independent removable outer stationary grate-sections, each comprising a vertical web, and obliquely-inclined transverse teeth projecting outward and upward, and inward and downward, from the opposite sides of said web, and held in the sockets of said frame, free from extraneous fastening devices.

3. In a shaking and dumping grate, the combination with a series of independent legs, each provided with enlarged bases, central vertical webs and cross-heads, of end frames having downward-forked flanges for engagement with said webs, horizontal flanges projecting above said forked flanges, and vertical angle-flanges above the said horizontal

flanges, side and central bearing-bars having 20 cross-heads at their ends for engagement with the angle-flanges on the end frames, flanges with right-angular bottom extensions for receiving the stationary grate-sections, and projecting hubs for receiving the movable grate-sections, all adapted to be held together in operative position by the interlocking of the various parts named free from extraneous fastening devices. 25

In testimony that I claim the foregoing I have hereunto set my hand, at Milwaukee, in the county of Milwaukee and State of Wisconsin, in the presence of two witnesses.

GEORGE M. CONWAY.
